UNITED STATES PATENT OFFICE.

FRANK HYDE CHISHOLM, OF CHICAGO, ILLINOIS.

EXHAUST-VALVE.

No. 895,073.

Specification of Letters Patent.

Patented Aug. 4, 1908.

Application filed August 6, 1906. Serial No. 329,301.

To all whom it may concern:

Be it known that I, FRANK HYDE CHISHOLM, a citizen of the United States, residing at Chicago, in the county of Cook and State 5 of Illinois, have invented certain new and useful Improvements in Exhaust-Valves, of which the following is a specification.

My invention relates to exhaust valves for radiators, high pressure drip traps, and other 10 similar devices, in which it is desirable to allow the water and air to drain out of the system, but to prevent the passage of steam, and the invention has for its objects; to provide an improved valve of this type in which 15 the float for controlling the water valve is protected from the sudden inrush of steam or water; to provide a valve in which air may be admitted and vented independently of the water, and in which the water collected in 20 the casing will never interfere with the admission of air thereto or the venting of air therefrom; to provide a balanced and rapidly operating water exhaust valve arrangement, and finally, to provide a compact and simple 25 valve which shall be effective and reliable in operation. These and other objects are accomplished by my invention, one embodiment of which is illustrated in the accompanying drawings in which—

30 Figure 1 is a transverse section through the valve;

Figure 2 is a plan view with the cap removed,

35 Figure 3 is a detail section illustrating the air exhaust valve—the thermostatic closing means being omitted, and

Figure 4 is a longitudinal section through the air valve at right angles to the section of Figure 3.

40 As illustrated in the drawings, 4 is the valve casing provided at 5 with an admission connection leading from the radiator, and at 6 with a connection with the vacuum return, a drain, or the atmosphere. The top of the 45 casing is removable from the body thereof, to allow ready access to the interior part, and consists of the cap 7 which is screw-threaded into the body portion of the valve. The vacuum return or exhaust opening 6 is 50 connected with a sort of a pocket 7' on the interior of the casing, which pocket is provided with a pair of valve openings 8 and 9 for the passage of water to the vacuum return, a drain, or the atmosphere, and with 55 the passage 10 leading to the casing 11 in which the thermostatic air exhaust valve is

located. Referring first to the water exhaust valve, such valve comprises, as indicated in Figures 1 and 2, a pair of valves 12 and 13 carried by the valve stem 14, which 60 valve stem is pivotally connected to the lever 15 pivoted at 16 to the projecting stud 17, and provided at its outer end with the float 18 which may be of any preferred form and is adapted to keep the valves closed by 65 its weight when the casing is empty, and open such valves 12 and 13 when the water in the casing reaches a certain predetermined height. The air exhaust valve 19 is inclosed in the casing 11 leading to the opening 10, previously referred to, and such valve comprises a plug 19 of expandable material such as carbon, secured in the casing and having a reduced upper end 20 fitting a correspondingly reduced opening in the head 70 21' of the casing, which is screw-threaded to the portion 11. This valve is of the usual construction, and is so arranged that when air is passing through adjacent the valve, such valve will be of such a temperature as 75 80 to be contracted and allow air to pass through the passage and out through the pocket 7' and outlet opening 6, but when the casing is filled with steam the valve 19 will expand, closing the opening in the head 21' and preventing any further egress of the steam. Located adjacent to the admission opening 5 is the baffle plate 21, which baffle plate extends downwardly toward the bottom of the casing and is provided at its upper end with 90 an air port 22. The purpose of this baffle plate 21 is to prevent a sudden inrush of the water or steam from the admission opening impacting against the float 18, and the air port 22 at the upper end of such baffle plate 95 21 serves to admit air to the casing after the water in the casing has risen above the level of the bottom of the baffle plate. This arrangement permits of the exhaust of the air into the casing and also the venting thereof from 100 the steam line, regardless of the height of the water in the casing, and secures at all times, a uniform pressure on the interior of the casing and the system leading to the portion 5. The provision of the two valves 12 and 13, 105 the one on the outside of the pocket, and the other on the inside, gives a balance valve, as the pressure on the top valve 12 is counterbalanced by that on the lower valve 13, and the valve is not only more easily worked, 110 but provides for a more rapid exhaust of the water than would be the case if only a single

valve opening were provided. The part 23 is a needle valve whereby the casing may be blown out and cleaned from time to time.

In Figure 3 a detail modification of a different form of air exhaust valve is shown. In this modification, the expansible plug is omitted, thereby providing a continuous opening through the head 21'. This arrangement of course, permits of a constant leakage of steam, but the amount is so small as to be of slight importance.

Having thus described my invention and illustrated its use, what I claim as new and desire to secure by Letters Patent, is the following:

In combination, a casing provided with admission and exhaust openings, a pocket connected with the exhaust opening and ex-

tending into the casing and having valve openings in the opposite faces, a valve stem provided with valves fitting such openings, one valve being on the outside of the pocket and the other on the inside thereof, a float for actuating the valve stem, an air tube mounted upon the pocket and communicating therewith and with the interior of the casing, and a thermostatic valve in the air tube for controlling the passage therethrough.

In testimony whereof I have hereunto signed my name in the presence of the two subscribed witnesses.

FRANK HYDE CHISHOLM.
